Patented June 11, 1918.

UNITED STATES PATENT OFFICE.

JOHN D. NIELSON, OF LYNDHURST, NEW JERSEY.

GAME APPARATUS.

1,269,494.

Specification of Letters Patent. Patented June 11, 1918.

Application filed October 29, 1917. Serial No. 199,132.

To all whom it may concern:

Be it known that I, JOHN D. NIELSON, a citizen of the United States, and a resident of Lyndhurst, in the county of Bergen 5 and State of New Jersey, have invented a new and Improved Game Apparatus, of which the following is a full, clear, and exact description.

Among the principal objects which the 10 present invention has in view are: to provide an amusement apparatus having an educational feature; to promote interest in history and geography while affording amusement; and to simplify the construction 15 and cheapen the cost of a game apparatus for accomplishing the purposes above stated.

Drawings.

20 Figure 1 is a top plan view of a game-board constructed and arranged in accordance with the present invention;

Fig. 2 is a cross section of the same, the section being taken as on the line 2—2 in 25 Fig. 1;

Fig. 3 is a longitudinal section of the same, the section being taken as on the line 3—3 in Fig. 1;

Fig. 4 is a detail view on an enlarged 30 scale and in section, showing the apparatus by which the game is played, the section being taken as on the line 4—4 in Fig. 1.

Description.

35 As seen in the drawings, a wooden block 9 has formed therein, preferably by routing, a series of channels 10, 11, 12, 13, 14 and 15. The channels 11 to 15, inclusive, terminate in round pockets or chambers 16, 17, 18, 19 40 and 20. The above-mentioned channels are separated by vertical walls or partitions all terminating at the top of the block and opening on to a field 21 to afford access therefrom for a rolling object, such as a ball 45 22, when the same is ejected from a toy cannon, which, as shown in the drawings, is permanently located at the lower end of the channel 10.

The field 21 communicates with an inner 50 field 23 by means of a passage, at one side whereof is a blind channel 24. Opening from the field 23 at either side thereof, are other blind channels 25 and 26. The channels 25 and 26 are located at opposite sides 55 to the entrance of channels 27, 28 and 29,

respectively. The channels 27, 28 and 29 lead into pockets 30, 31 and 32.

As indicated, the game is played with a 60 rolling object, such as the ball 22. One or more such balls may be used and when inactive are held in a square recess or pocket 33.

The various pockets 16, 17, 18, 19, 20, 30, 31 and 32 have assigned thereto and preferably provided thereon, the names of towns and districts located or situated in some 65 country.

The game when played has a military significance, such that the object in firing the ball 22 from the cannon 40, is to bombard 70 some one of the cities or fortifications named. The ball 22 passes up through the channel 10 into the field 21, where due to the curved wall at the upper boundary of said field, the ball is partially returned toward the various channels 11 to 15 and 75 30 to 32, respectively.

It will be found that some skill as well as chance becomes a factor in the successful contest promoted by the game, which lends an added interest thereto. The educational interest which is promoted is intensified by the fact that the military significance is associated with the campaign in which the towns or fortified locations have a bearing. 80

The geographical interest is naturally promoted by curiosity awakened in the player as to the actual location of the city, town or district indicated by the means of the various pockets. 90

The chance of the ball passing into the blind channels 24, 25 and 26, adds the element of failure to the game, it being intended that when the ball is arrested in any of these channels, the play is lost to the 95 player, as the failure in an attack in a military campaign is lost in the endeavor to subdue any point.

To induce the ball 22 or other rolling object to seek the various channels and 100 pockets enumerated, the block 9 is raised at the upper end by means of the rail 34. The block 9 is provided with wedge-shaped side pieces 35.

The pleasure of the game is promoted by 105 providing the cannon with a spring-actuated plunger 36. The plunger 36 has a handle or knob 37, which is engaged by the player to retract said plunger against the expansion of the spiral spring 38. When 110

and as the plunger 36 is retracted from under the tubular turret 39 in which the ball 22 is deposited, said ball falls into the barrel of the cannon and because of the 5 uptilt of the block 9 and cannon which is fixedly attached thereto, the ball rolls back to the retracted position to rest against the plunger 36. When now the player releases the knob 37, the spring 38 projects the 10 plunger 36 and ejects with varied violence, the ball 22 for its flight up the channel 10.

Claim.

As an article of manufacture, a game ap-

paratus comprising a solid block having 15 formed therein a series of open-ended channels, the ends of said channels converging upon a field portion, the floor of said field portion being flush with the bottoms of said channels, one of said channels having a 20 curved wall for the delivery of a rolling ball, the delivery end of said wall having a return curve for projecting the ball upon said field portion, the walls of said channels being integral with said block and the upper 25 edges of said walls being flush with the upper surface of said block.

JOHN D. NIELSON.
